INVENTOR

BY Victor J. Evans

ATTORNEY

UNITED STATES PATENT OFFICE

WALTER HELEZER, OF CHICAGO, ILLINOIS, ASSIGNOR OF ONE-TENTH TO JOSEPH ZAJACZEK, OF CHICAGO, ILLINOIS

ENVELOPE

Application filed April 21, 1928. Serial No. 271,918.

This invention relates to certain novel improvements in envelopes, and has for its principal object the provision of an improved construction of this character which will be economical in manufacture and which will be arranged such that unauthorized opening thereof without evidence of such opening will be prevented.

Another object of my invention is to provide an envelope of the above named character which may be arranged such that the usual flaps employed to provide the sides of an envelope may be omitted so as to afford considerable saving in the material.

15. A further object of the invention is to provide a means for joining the edges of an envelope formed from a blank of the above named character which will be arranged such that unauthorized opening thereof will be prevented.

A further object of the invention is to provide a device which may be associated with the flap of the envelope in order to facilitate the sealing of said flap and to arrange this device in such a manner that it will serve as a detecting element so as to reveal tampering with the envelope.

A still further object of the invention, ancillary to the foregoing, is to provide a device of the above named type which will be arranged in such a manner that it may be associated with an envelope of any desired shape or form.

35. Other objects will appear hereinafter.

The invention consists in the novel combination and arrangement of parts, to be hereinafter described and claimed.

The invention will be best understood by reference to the accompanying drawings, wherein a preferred form of construction is shown, and in which:

Fig. 1 is an elevational view depicting the blank from which a preferred embodiment of my invention is associated;

Fig. 2 is a view of an envelope formed from the blank disclosed in Fig. 1, showing the flap in open position;

Fig. 3 is a view substantially similar to Fig. 2 showing the flap in closed position;

Fig. 4 is a sectional view taken substantially on the line 4—4 on Fig. 3;

Fig. 5 is a view depicting a modified form of construction;

Fig. 6 is a sectional view taken substantially on the line 6—6 on Fig. 5; and

Figs. 7 and 8 are elevational views depicting a further modified form of construction for my invention.

In the drawings, and more particularly in Figs. 1 to 4 inclusive, I depict an envelope which includes a front portion 10 which has a rear portion 11 and a flap portion 12 connected thereto along the transverse edges thereof. A fold line 13 is provided at the juncture between the front 10 and the rear portion 11 and a fold line 14 is provided between the juncture of the front portion 10 and the flap 12. The envelope is adapted to be formed by folding the back portion 11 along the line 13 in such a manner that it will be disposed over the fold portion 10. The open side edges are then closed by suitable stitching indicated by 15 in the drawings. Preferably, this stitching is started on the flap 12 at substantially the mid-point in the extent thereof and extends along said flap and down one side and then across the envelope above the fold line 13 and then up the opposite side and then across the flap 12 to substantially the mid-point thereof. In this manner, the ends of the stitching are disposed on the inner side of the flap 12. These ends are adapted to be arranged so as to be prevented from displacement and one method of accomplishing this is disclosed in Fig. 2, wherein it is shown that a suitable strip of paper or the like indicated by 16 in the drawings is adhesively secured over the ends of the stitching so as to prevent displacement thereof. It is to be understood however, that these ends might be joined in any desired manner as by mounting or the like and still not depart from the purview of my invention. It is apparent from the foregoing that, in order to attain access into the interior of the envelope, it will be necessary to break the stitching, which obviously would afford a

95

100

means of detecting tampering for it is apparent that after the flap has been folded over to the position illustrated in Fig. 3, the ends of the stitching are positioned thereunder, and thus displacement of these 5 ends is prevented.

As best illustrated in Figs. 2 and 3, the side of the flap which is adapted to be disposed in engagement with the portion 11 when said flap is moved to closing position 10 is provided along the edge thereof with a suitable adhesive indicated by 17. Preferably, the flap 12 is provided with a tongue portion 18 at substantially the mid-point thereof. In the back portion 11 at substantially 15 the point best illustrated in Fig. 1, a slot 19 is provided which is arranged so as to provide a relatively short tongue portion 20. My detecting device includes a sheet of transparent material 21 which is 20 preferably formed of a transparent paper, and this detecting device also includes a sheet of relative thin tissue or rice straw paper, indicated by 22 in the drawings, which is adapted to be mounted below the 25 sheet of transparent material 21. Preferably, on the sheet of material 22 on the side thereof disposed toward the sheet of material 21, I provide suitable indicia such as a 30 firm name or the like which is imprinted thereon in any approved manner and this indicia is indicated by 23 in the drawings. The sheets of material 21 and 22 are adapted to be disposed on the outer face of the back portion 11 and are preferably arranged such 35 that the lower edge thereof will be disposed in the notch 19 in order that the tongue 20 will extend across these sheets of material as best illustrated in Fig. 2. Suitable stitching 40 is then provided which is indicated by 24 in the drawings and this stitching is adapted to extend around the edges of the sheets of material 21 and 22 so as to hold said sheets of material in position and this stitching is adapted to extend across the 45 upper side of the tongue portion 20. This stitching 24 extends only along three sides of the material 21 and 22 so as to leave the edge covered by the edge of the tongue portion 22 open and the ends of this stitching 50 24 are extended upwardly from the sides of the sheets of material and preferably, the ends are knotted or similarly secured interiorly of the envelope so as to prevent displacement thereof. The portion of the 55 tongue 18 along the edges thereof and on the side opposite that provided with the adhesive 17 is provided with an additional adhesive substance indicated by 25 in the drawings. The adhesive substance 17 and 60 25 are preferably of the type which will be adherent when moistened and therefore, by moistening these adhesives and positioning the flap 12 as indicated in Fig. 3 such that 65 the tongue 18 will extend through the open

edge of the sheets of material 21 and 22 so as to be disposed therebelow, it is apparent that the flap 12 may be secured in position. The adhesive substance 17 will adhere to the portion 11 and thus secure the flap 12 in 70 position. The adhesive substance 25 will adhere to the sheet of material 22. It is apparent that since the sheet of material 22 is formed of a relatively thin paper, that displacement of the tongue portion 18 will 75 be prevented without destroying this sheet of material 22, which will obviously afford an expeditious manner of detecting unauthorized tampering with the envelope. This sheet of material is preferably of such a 80 thickness and of such a constituency that the usual soaking or steaming will result in the destruction thereof and will also cause blurring of the indicia 23 printed thereon. It is apparent that the detecting member comprising the sheets of material 21 and 22 and the stitching 15 will effectively seal an 85 envelope and will readily detect any unauthorized tampering therewith.

In Fig. 5, I have depicted a modified form 90 of construction. In this instance, the main front portion of the envelope is provided with side flaps 26 which are bent to extend over the rear portion of the envelope, it being understood that similar reference characters are used in this figure to indicate 95 similar parts to the parts illustrated in Figs. 1 to 4 inclusive. These flaps 26 may, if desired, be adhesively secured to the face of the rear portion 11 and in addition to this suitable staple fasteners indicated by 27 in the drawings may be passed through these flaps 26 and the rear wall 11 in such a manner that the ends of the staple members 27 100 will be disposed interiorly of the envelope. Similar staple members 28 are employed to position the sheets of material 21 and 22 and it is therefore apparent that the sheets of material 21 and 22 will co-operate with the tongue portion to detect unauthorized tampering with the envelope and it is also apparent that the staple members 27 and 28 are to co-operate due to the fact that the limb 105 portions thereof are disposed so as to be inaccessible.

In Fig. 7, a further modified form of construction is shown and in this instance, an envelope is provided which includes the usual side flaps 28. Staples, substantially similar 110 to the staples 27 and indicated by 29 in the drawings, are arranged so as to lock the ends of the flaps 28 and also the sheets of material 21 and 22 in position and a similar staple is employed to lock the tongue portion 20 and the sheets of material 21 and 22 115 in position. It is, therefore, apparent that this device will function in substantially the same manner as the device illustrated in Fig. 5 to prevent unauthorized tampering 120 125 130

with the envelope since it will detect any tampering.

In Fig. 8, a further modified form of construction is shown. In this instance, an envelope is provided which includes the usual end flaps 30. The rear side 11 and the sheets of material 21 and 22 are adapted to be secured in the same manner as was carried out in Fig. 1 and 4 inclusive. However, additional stitching indicated by 31 is provided which is adapted to extend diagonally across these sheets of material 21 and 22 so as to provide four pockets therebelow which are disposed in cooperating pairs. The horizontally disposed pairs of pockets are arranged such that the lowermost thereof is secured below the tongue 20 and the pocket opposite this pocket is adapted to receive the tongue portion 18 of the flap 12 in the usual manner. The side flaps 30 are adapted to be inserted into the remaining of the pockets and these side flaps 30 are provided with an adhesive substance indicated by 32 on the face thereof so as to be secured to the rear portion 11 and in addition to this, these flaps 30 have an adhesive provided adjacent the apex which is indicated by 23 in the drawing and which is substantially similar to the adhesive indicated by 25 and which serves a similar purpose. It is therefore apparent that this envelope has all movable portions thereof associated with the detecting device comprising the sheets of material 21 and 22 and therefore, any unauthorized tampering with this envelope will be indicated by these sheets.

It is apparent from the foregoing description, that I have provided an envelope which will be arranged in such a manner that unauthorized tampering with the envelope such as attempt to open it will be indicated on detecting portions provided thereon and these detecting portions will be arranged such that evidence of tampering will be readily apparent.

While I have illustrated and described the preferred form of construction for carrying my invention into effect, this is capable of variation and modification without departing from the spirit of the invention. Therefore, I do not wish to be limited to the precise details of construction herein set forth, but desire to avail myself of such variations and modifications as come within the scope of the appended claims.

Having thus described my invention, what I claim as new and desire to protect by Letters Patent is:

1. In a device of the class described, an envelope including a flap portion, means adapted to receive a portion of said flap when said flap is disposed in closing position, said means including a sheet of transparent material and a sheet of relatively thin and weak paper adapted to be mounted

below said transparent sheet whereby the portion of said flap inserted thereunder may be adhesively secured thereto.

2. In a device of the class described, an envelope including a flap portion, means adapted to receive a portion of said flap when said flap is disposed in closing position, said means including a sheet of transparent material and a sheet of relatively thin and weak paper adapted to be mounted below said transparent sheet whereby the portion of said flap inserted thereunder may be adhesively secured thereto, and means for securing said sheets of materials to the back of said envelope.

3. In a device of the class described, an envelope including a front portion and a rear portion hingedly connected thereto along one end thereof and flap portions adapted to be hingedly connected to said front portion, a sheet of transparent material, a sheet of relatively thin and weak material disposed below said sheet of transparent material, means for securing said sheets of material to the back of said envelope whereby said flaps may be inserted thereunder so as to be adhesively secured to said sheet of relatively thin and weak material.

4. In a device of the class described, an envelope including a front portion and a rear portion hingedly connected thereto along one edge thereof and flap portions adapted to be hingedly connected to said front portion, a sheet of transparent material, a sheet of relatively thin and weak material disposed below said sheet of transparent material, means for securing said sheet of material to the back of said envelope whereby said flaps may be inserted thereunder so as to be adhesively secured to said sheet of relatively thin and weak material, said back portion having a notch portion formed therein providing a tongue adapted to be inserted over said sheets of material whereby to locate and hold said sheets of material in position.

In testimony whereof I affix my signature.

WALTER HELEZER.
